Inventor:
John M. Larson

By Jones Addington Ames & Leibold
Attest.

UNITED STATES PATENT OFFICE.

JOHN M. LARSON, OF CHICAGO, ILLINOIS, ASSIGNOR TO NATIONAL REGULATOR COMPANY, OF CHICAGO, ILLINOIS, A CORPORATION OF ILLINOIS.

REGULATING DEVICE.

Application filed June 15, 1923. Serial No. 645,620.

To all whom it may concern:

Be it known that I, JOHN M. LARSON, a citizen of the United States, residing at Chicago, in the county of Cook and State 5 of Illinois, have invented new and useful Improvements in Regulating Devices, of which the following is a full, clear, concise, and exact description, reference being had to the accompanying drawing, forming 10 a part of this specification.

My invention relates to a regulating device, and more specifically it relates to a diaphragm-cell-actuator.

One of the objects of my invention is to 15 provide a diaphragm-cell-actuator in which the individual cells are constructed as independent units, unconnected and noncommunicating with respect to each other and readily removable from the stack.

20 This construction has two distinct advantages: (1) If a cell is damaged it can be readily removed and repaired or replaced by a new cell without disturbing the other cells in the stack; (2) injury to a single cell does 25 not affect the operativeness of the other cells, as is the case where the cells are in communication with each other. It has another advantage also in that the diaphragms are flexible throughout their entire extent, as is 30 not the case when the cells are connected together.

A further object of my invention is to 35 provide improved means whereby the entire stack of cells may be easily and quickly removed from the well for the purposes of repairing, testing, etc. Further objects will follow from the description and the appended claims.

40 In the drawings in which an embodiment of my invention is shown—

Figure 1 is an axial sectional view showing the diaphragm cage and well;

Fig. 2 is an enlarged axial view through the stack of diaphragm cells; and,

45 Fig. 3 is a section on the line 3—3 of Fig. 2 showing how the individual cells are removed.

50 Referring now to the drawings in detail the construction shown therein comprises a stack of superposed, unconnected, non-communicating diaphragm cells 10, a cage 11 containing the diaphragm cells to facilitate handling them collectively, a casing or well 12 in which the cage and cells are con-

tained, a plunger head 13 engaged by the 55 uppermost diaphragm cell and actuated by the stack of cells, a lever 14 actuated by the plunger head, and a bonnet or cap 15 on the casing 12, through which the plunger rod 16 extends and on which the lever is 60 pivotally mounted at 17.

One of the uses of such an actuator might be to control the damper of a heating plant, the well 12 being screwed into the wall 18 of the boiler, so that the inner portion of the 65 well would be exposed to the temperature within the boiler whereby the diaphragm cells 10 would be affected by the boiler temperature. There are of course many other locations where such a construction could 70 be used.

As shown in detail in Fig. 2, the individual diaphragm cells are unconnected and non-communicating with respect to each other so that one of the cells may be readily 75 removed from the stack without removing the others for testing, repairing, etc.

As shown in Fig. 3, the bars 18^a of the cage 11, may be sprung outwardly, as indicated in dotted line on Fig. 3, to permit 80 the removal of the cells 10.

In order to center the cells with respect to each other and maintain them in alignment, they are provided with interengaging 85 depressions and projections, the projections 19 on the cell underneath engaging the depression 20 in the cell above.

Each of these cells has placed therein a small quantity of volatile liquid, after which it is hermetically sealed. To permit this, 90 each cell is provided with a countersunk filling hole formed by pressing the sheet metal inwardly, after the liquid is placed in the cell, the countersunk hole is closed by a drop of solder as indicated at 21. This 95 form of closure construction is very rugged and reliable due to the countersinking of the walls of the opening and the thickness of the solder plug which results from this countersinking.

The cage 11 in which the diaphragm cells 10 are contained not only serves as a convenient means for handling the cells collectively but also serves to prevent injury to the cells by over-expansion. Thus no matter 105 what the rise in temperature, the cells can not expand beyond a certain point, that is the point at which the plunger head 13 en-

gages the annular head 22 of the upper end of the cage. This prevents the expansion of the individual cells beyond a certain limit.

In order to lessen the strain on the rivets 5 23 which secure the cage bars 18^a to the cage-head 22, I so locate these rivets that they will be engaged by the plunger head 13, at the limit of its upper movement, thereby relieving the tensile strain on these 10 rivets.

If it is desired to get to the diaphragm 15 cells for inspection or repair, all that is necessary to do is to take off the bonnet 15 and lift the cage 11 out of the well. The 15 individual cells can then be removed from the cage laterally, as indicated in Fig. 3. The stem 16 and bonnet 15 may be used as a sort of handle for withdrawing the cage 11 from the casing 12.

20 It will be seen that I have thus provided a diaphragm-cell-construction in which the individual cells may be readily removed and repaired or replaced without disturbing the other cells in the stack; in which the dia- 25 phragm cell is flexible throughout its entire extent; in which the unconnected cells are maintained in alignment with each other, and in which the entire stack of cells can be readily handled collectively.

30 While I have shown but one form of my invention, it is obvious that it may be embodied in other forms covered and defined by the claims.

Having thus described my invention, what 35 I claim as new and desire to secure by Letters Patent of the United States is:

1. A heat controlled actuating device comprising a cage and a plurality of superposed, unconnected non-communicating expansible 40 cells in said cage, said cage comprising a plurality of longitudinally extending spring bars embracing said cells and yieldable laterally to permit the removal of the cells from said cage.

45 2. A heat controlled actuating device comprising a cage, a plurality of superposed, un-

connected, non-communicating expansible cells in said cage, and a plunger head actuated by said cells, said cage comprising a plurality of longitudinally extending bars, 50 embracing said cells, and a ring to which the ends of said bars are riveted, the ends of the bars being bent inwardly and the heads of the rivets being engageable by said plunger head to relieve the tension on the rivets 55 when the cells are expanded to the capacity of the cage.

3. A heat controlled actuating device comprising a casing, a cage in said casing readily removable therefrom, a plurality of superposed unconnected expansible cells in said cage readily removable therefrom, and a plunger head in said cage actuated by said cells but disconnected therefrom, and provided with an actuating stem extending 60 from said casing, whereby said actuating stem may be used to withdraw the cage from the casing.

4. A heat controlled actuating device comprising a stack of superposed unconnected, 70 noncommunicating expansible cells, the walls of said cells being of thin flexible sheet metal to permit expansion and contraction of the cells, said thin flexible sheet metal walls being shaped to provide nested inter- 75 engaging projections and depressions for centering the cells with respect to each other.

5. A heat controlled actuating device comprising a stack of superposed unconnected, 80 noncommunicating expansible cells, the walls of said cells being of thin flexible sheet metal to permit expansion and contraction of the cells, said thin flexible sheet metal walls being shaped to provide nested inter- 85 engaging centrally located projections and depressions for centering the cells with respect to each other.

In witness whereof, I have hereunto subscribed my name.

JOHN M. LARSON.
